W. A. Skinkle

Inventor,

Peter K. Dederick

UNITED STATES PATENT OFFICE.

PETER K. DEDERICK, OF ALBANY, NEW YORK.

BALE-TIE.

SPECIFICATION forming part of Letters Patent No. 230,620, dated August 3, 1880.

Application filed March 10, 1879.

To all whom it may concern:

Be it known that I, PETER K. DEDERICK, of Albany, county of Albany, State of New York, have invented certain new and useful 5 Improvements in Bale-Bands and Bale-Tie Fastenings; and I do hereby declare that the following is a full, clear, and exact description of the same, reference being had to the accompanying drawings, forming a part of this specification, and in which—

Figure 1 represents the ends of one of my improved bale-bands and bale-tie fastenings as they appear when completed for use; and Fig. 2 represents a bale with my improved 15 bale-bands and bale-tie fastenings secured thereto and in process of being secured thereto, as will be hereinafter more fully described.

To enable those skilled in the art to which my invention belongs to make and use the 20 same, I will proceed to describe my said invention more in detail.

My present invention relates to metallic bands for baling purposes, formed from wire or band-iron, with a pliable connection or fastening for drawing them taut and securing them 25 in position about the bale, as will be herein-after more fully described.

As a preliminary explanation, I will state that in baling hay and other loose material to 30 be shipped by railroads in their ordinary cars used for such purposes it is customary, for various obvious reasons, to use very light wire for binding the bales, so that they will be relieved by stretching somewhat, and when this 35 is done the cars may still be loaded to their weight-transporting capacity. Consequently the additional cost of heavy ties or bale-bands is saved, and very light cheap bands of small wire are made to subserve the required purpose.

40 In baling cotton or other material to be transported in vessels where the weight to be carried is not limited, as in railroad freight-cars, it is an object to reduce the material to the smallest possible compass, and to confine it 45 securely in such compressed condition. Hence the metal bands, whether made of wire or band-iron, must be of such size and weight as not to stretch or break; and it has been found in practice very difficult to draw the bands in 50 such cases sufficiently taut, and also very difficult to secure and retain them in position by

the ordinary modes in use previous to my present invention, owing to the stiff and unyielding nature of the material used in the construction of such old bale-bands and bale-tie 55 fastenings; and the nature of my invention consists in the combination, with the main body of the bale band or tie, of a pliable fastening-connection, which enables the operator to secure and fasten the band about the bale while 60 in a compressed state in such a manner as to prevent all slack or slipping of the bale bands or ties or their connections after the bale has been removed from the press.

In the drawings the part marked A represents the main body of the band, which, when used for baling cotton, should be heavy wire. The ends are returned and twisted to form loops B B, and a strong cord or rope, C, is secured to one end, as indicated in Fig. 1, the 65 ends of the cord or rope C being left of sufficient length, as indicated by C' C', for properly fastening the looped ends B B together after the band or tie has been placed about the bale, as indicated in Fig. 2 of the drawings, and in 70 which figure the band upon the right-hand side is shown in position with its flexible connection run through the looped ends B of the band A, ready to be knotted or tied by the 75 operator after the band has been drawn up so as to take up all the slack, as indicated on the left-hand side of Fig. 2.

The central band, D, of Fig. 2 represents the invention applied to a band or tie the body of which is made of band-iron, the ends being 80 riveted back to hold the loops E E, which are fastened together by means of a cord or rope, C, the same as the ends B B of the tie or band A are fastened together.

It will be observed that the cord or rope C 85 can be passed back and forth through the loops, thereby securing a tackle-purchase, which enables the operator to take up all the slack and fasten the ends of the tie or band together about the bale in a secure and convenient 90 manner while it is under pressure.

The wire of which the band and loops are 95 formed is of sufficient size, so that the cord or rope will render freely during the operation of drawing up the slack and fastening the band 100 about the bale; but small spools of metal or other suitable material may be slipped on the

wires, so as to be in the loops when formed, to prevent undue friction, and in lieu of loops rings or other metal connections of suitable shape and size may be used, if desired, for receiving and holding the flexible or pliable cord or rope part.

Those skilled in the art to which my invention belongs will readily perceive that the weathering of the cord or rope not only ¹⁰ cures the power to draw the band taut, but also furnishes the purchase to hold it in place, and that a slight pressure of the thumb of the operator at the loop will prevent the fastening slipping during the operation of securing or ¹⁵ knotting the parts together, as shown in the left hand of Fig. 2.

It will be understood that in lieu of a cord or rope soft fine wire, leather, or any other suitable pliable material may be employed, and ²⁰ that it may be fastened to the end of the bale band or tie in any suitable manner.

Having thus fully described my invention, what I claim, and desire to secure by Letters Patent, is—

²⁵ 1. The combination, with one end of a sin-

gle and narrow metallic bale band or tie, of a flexible or pliable tie end, C, of cord or other similar material, permanently fastened to the end of the metallic band or tie, for the purposes set forth.

³⁰ 2. A single and narrow metallic bale band or tie, A, provided with looped ends by returning and twisting the ends with the body of the tie, as described, and having a flexible or pliable tie part or end, C, permanently secured to one of its loops for connecting or securing the band about the bale, as herein shown and described.

³⁵ 3. The method of adjusting, straining, and securing baled material by means of the pliable connection C, securely fastened to one end of the metallic part of the tie and interlocked or laced by means of its free end with the other loop of the metallic part of the tie, as and for the purposes shown and set forth.

PETER K. DEDERICK.
